UNITED STATES PATENT OFFICE.

ESTHER JANE TRACY, OF WAVERLY, ILLINOIS.

DESIGN FOR A HEAT-DEFLECTOR FOR HOT-AIR REGISTERS.

SPECIFICATION forming part of Design No. 30,059, dated January 24, 1899.

Application filed December 27, 1898. Serial No. 700,461. Term of patent 3½ years.

To all whom it may concern:

Be it known that I, ESTHER JANE TRACY, a citizen of the United States, residing at Waverly, in the county of Morgan and State of Illinois, have invented and produced a new and original Design for a Heat-Deflector for Hot-Air Registers, of which the following is a specification.

This invention relates to a new and original design for a heat-deflector for hot-air registers; and it has for its object to provide a design of this character that shall be both useful and ornamental.

The leading feature of the design resides in a flaring hood having a flat rectangular inclined deflecting-plate provided at opposite side edges with parallel triangular side wings projecting beyond the plane of the inner side of the deflecting-plate, said triangular side wings having their hypotenuse edges sloping from the wide or base ends of the wings to the rear edge of the deflecting-plate.

The minor features of the design are the deflecting-plate, having the side wings bent therefrom at right angles and provided in the outer side thereof with a raised rectangular bead, and an additional feature of the design is an inturned continuous bead following the inner peripheral edge of the entire hood, including the edges of the deflecting-plate as well as the edges of the triangular side wings thereof.

In the drawings, Figure 1 is a front perspective view of a heat-deflector embodying

the design contemplated by the present invention. Fig. 2 is a rear perspective view of the same. Fig. 3 is a transverse sectional view of the deflector.

Referring to the accompanying drawings, the numeral 1 designates a flaring hood having a flat rectangular inclined deflecting-plate 2, provided on the outer side thereof with a raised rectangular bead 3, forming the margin of a plain rectangular panel 4. At opposite side edges the rectangular deflecting-plate 2 of the hood has bent therefrom at right angles the oppositely-located parallel triangular side wings 5. These side wings project beyond the plane of the inner side of the deflecting-plate 2 and have the hypotenuse edges 6 sloping from their wide or base ends to the straight rear edge 7 of the deflecting-plate.

To complete the design, the entire hood is provided with an inturned peripheral bead 8, following the inner peripheral edges of the deflecting-plate and the triangular side wings thereof.

What is claimed is—

The design for a heat-deflector for hot-air registers, herein shown and described.

In testimony that I claim the foregoing as my own I have hereto affixed my signature in the presence of two witnesses.

ESTHER JANE TRACY.
